GASEOUS FLUID VAPORIZER AND MIXER

Herbert E. Bucklen, Elkhart, Ind.

Application May 5, 1930, Serial No. 449,844

5 Claims. (Cl. 48—180)

This invention relates to gaseous fluid vaporizers and mixers for liquid fuel, and more particularly to an improved means for causing the admixture of hydrocarbon fluid and air in an efficient manner after the hydrocarbon fluid has been carbureted prior to its introduction into a combustion chamber to the extent that the mixture will be in the form of substantially a dry mist.

10 While the invention is herein disclosed as being applied to intake manifolds of internal combustion engines, it is to be understood that it is not limited thereto inasmuch as it may be utilized wherever it is desired to efficiently vaporize and 15 mix hydrocarbon fluids for combustion purposes such, for example, as in oil burning furnaces and the like.

It is to be further understood, that the term "internal combustion engine" as herein employed 20 shall not be construed as being limited to that type of engine wherein a charge is introduced into the combustion chambers by suction produced by the action of the pistons, the charge then compressed and subsequently exploded by igniting by 25 an independent instrumentality, but is intended to include fuel injection type internal combustion engines operating on the Diesel principle.

Low grades of fuel now employed for the operation of internal combustion engines and other 30 purposes contain a large percentage of relatively non-volatile constituents which are not readily and completely atomized by the action of a carburetor. Such particles of fuel as are not completely atomized have a tendency to condense and 35 collect upon the walls of a fuel mixture conduit or manifold in the course of the passage of the carbureted fuel from the carburetor to the combustion chamber or chambers. This results in the feeding into the combustion chamber or chambers 40 of a mixture comprising globules of hydrocarbon fluid of appreciable size and since the combustion of globules of such a character is necessarily imperfect, there is a lack of efficient combustion resulting in accumulation of carbon 45 within the combustion chamber or chambers and associated parts.

Efforts directed to the alleviation of this condition have been only partially successful. Such efforts have been mainly concentrated in the direction of the interposition of means in a mixture conduit either to produce an atomizing effect 50 or to produce merely a turbulizing effect.

I have found that by properly combining a turbulizing effect with an atomizing effect upon 55 a fuel stream under high velocity, the resultant

turbulent mixture comprises a substantially dry mist whereupon subsequent combustion of the mixture results in maximum efficiency unaccompanied by undesirable carbonization of the combustion chamber and associated parts. 60

To this end, the invention contemplates the provision of a novel arrangement of a turbulator and vaporizer and mixer both of novel construction and arranged in such a relationship as to produce the desired result. More specifically, I 65 have provided a combined turbulator, vaporizer and mixer adapted to be interposed in a conduit preferably at the juncture of the outlet port of a carburetor and the inlet port of an intake manifold. The turbulator part comprises a plate-like 70 portion provided with a centrally disposed restricted passage the passage being of frustoconical configuration extending into the conduit in the direction of the flow of the carbureted mixture, the plate being provided with a plurality of 75 tangentially disposed grooves communicating with the receiving end of the Venturi opening for admitting air into the opening from the open atmosphere. Due to the tangential disposition of the grooves, air admitted to the receiving end of 80 the restricted passage causes a swirling or whirling of the carbureted mixture passing therethrough.

At the discharge end of the restricted passage, I provide a vaporizer and mixer comprising 85 coarse mesh retaining means including therebetween a promiscuously intertwined loose mass of metallic filaments preferably in the nature of steel shavings or steel wool. For a clear comprehension of the characteristics, function and results produced by such a mass of metallic filaments, reference may be had to my co-pending application Serial No. 441,453 filed April 4, 1930, for Gaseous fluid vaporizers and mixers. For the purposes of the present disclosure, it will suffice to say that inasmuch as the metallic filaments are promiscuously intertwined in a loose mass, the interstitial spaces extending therethrough do so in a promiscuous manner. Thus, 90 globules of carbureted hydrocarbon fluid passing therethrough will be not only cut up or shredded but will leave the mass in a haphazard or volleying condition. By positioning such a vaporizer and mixer at the discharge end of the restricted passage the carbureted mixture is introduced into the vaporizer and mixer in a turbulent condition, thus materially increasing the discharge of the mixture in a haphazard or volleying condition. It is to be understood, of course, 95 that such action as is outlined above takes place 100

105

110

under high velocity. The resultant stream of gaseous fluid emanating from the vaporizer and mixer comprises a thoroughly mixed and vaporized fluid conducted in a rapidly volleying, turbulent condition to such an extent that the mixture introduced into the combustion chamber of an internal combustion engine or the like, is in the nature of substantially a dry mist.

Preferably, the mechanism may be provided in two interfitting units. However, the salient features of the present invention may be embodied in a single structure as will be more readily apparent from the following detailed description of the invention.

The diverse advantages of the present invention will appear from the following detailed description of several preferred embodiments of the invention illustrated in the accompanying drawing in which:

Figure 1 is an elevation of a carburetor and intake manifold of an internal combustion engine in assembled relation, parts being broken away to show the position of the novel turbulat- ing, vaporizing and mixing means;

Figure 2 is an enlarged sectional view of the section illustrated in Figure 1;

Figure 3 is a bottom view of the turbulat- ing element;

Figure 4 is a vertical section through a modified form of turbulat- ing, vaporizing and mixing means; and

Figure 5 is a section taken along the line 5—5 of Figure 1.

Referring more particularly to Figures 1 to 3, inclusive, I have illustrated one form of application of the invention to an intake conduit or manifold of an internal combustion engine. The intake manifold 10, illustrated in Figure 1, is one of the character now generally employed in connection with four cylinder internal combustion engines and comprises a body portion 11 having the usual outlet ports 12 provided with suitable attaching flanges 13 and a centrally disposed inlet port 14, flanges 13 being suitably secured to the block or head 15 of an internal combustion engine as by means of bolts 16. A carburetor 17 of any suitable or preferred construction having an outlet port 18 provided at its end with an attaching flange 19 is suitably connected to inlet port 14 of the intake manifold 10 by means of suitable bolts 20 passing through attaching flange 21 of the intake manifold and flange 19 of the carburetor outlet port 18.

In the modification illustrated in Figures 1 to 3, inclusive, the turbulat- ing, vaporizing and mixing means comprises essentially two interfitting elements consisting of a turbulat- ing element 22 and a vaporizing and mixing element 23.

Turbulat- ing element 22 comprises a plate portion 24 conforming substantially to the configuration of the attaching portions 19 and 21 of the carburetor and intake manifold, respectively, and is provided with suitable ears 25 having suitable perforations 26 therethrough to accommodate the shanks of bolts 20. Centrally of the plate portion 24, the turbulat- ing element 22 is provided with a restricted passage 27 of substantially frusto-conical configuration extending upwardly therefrom, as illustrated in Figures 1 and 2. The underside of the plate portion 24 is provided with tangentially disposed grooves 28 suitably stamped or otherwise formed therein, grooves 28 extending from the periphery of plate portion 24 to the lowermost inner peripheral portion of the Venturi opening 27.

Two or more transverse recesses or perforations 29 are provided at the base juncture of the restricted passage 27 and the plate portion 24 for a purpose to be hereinafter described.

Vaporizing and mixing element 23 comprises a coarse reticulated mesh screen container 30 comprising a semi-spherical portion 31 having a laterally extending flange 32 and a frusto-conical base portion 33 having a similar flange 34. Prior to the assembly of the spherical portion 31 and the frusto-conical portion 33, a promiscuously intertwined loose mass of metallic filaments 35 in the nature of steel shavings or steel wool is interposed in the spherical portion 31. Flanges 32 and 34 are then suitably secured together by means of a U-shaped copper ring 36. Preferably, flanges 32 and 34, and ring 36 are of the configuration of plate portion 24 of member 22 conforming to the configuration of the attaching flanges 21 and 19 of the manifold and carburetor, respectively. The elongated portions of the flange of the vaporizing and mixing member 23 are provided with suitable perforations 37 coinciding with perforations 26 for the passage therethrough of bolts 20. As will be clearly evident from Figures 1 and 2, the flange portion of the vaporizing and mixing member 23 being copper covered will be suitably adapted as a gasket.

In assembled condition, turbulat- ing member 22 is seated with the underside thereof in engagement with the upper face of attaching flange 19 of the carburetor 17, the flange of the vaporizing and mixing element 23 being seated on the upper face of plate portion 24 of member 22 with the restricted passage 27 extending into the complementary frusto-conical portion 33 and attaching flange 21 of the intake manifold inlet portion 14 being seated upon the upper face of the flange of member 23 with the semi-spherical portion 31 thereof disposed upwardly within inlet conduit 14. Bolts 20 are then passed through the perforations in attaching flange 21, perforations 37, 26 and the perforations in the attaching flange 19 of the outlet port 18 of carburetor 17.

In operation, the stream of carbureted hydrocarbon fluid passes upwardly by virtue of the suction imposed upon the conduit by a piston on its down intake stroke, through the Venturi opening 27. At the same time air from the open atmosphere is admitted and drawn in through the grooves 28, and due to the tangential disposition of such grooves with respect to the restricted passage 27, a whirling action results imposing a swirl or whirl upon the carbureted hydrocarbon fluid seeking passage through the passage 27. It will be readily apparent, that the speed of passage through the passage 27 will be materially increased and due to the swirl or whirl set up in such Venturi opening, the whirling stream of carbureted fluid will enter and be received by the vaporizing and mixing element 23 in turbulent condition. The promiscuously intertwined loose mass of metallic filaments 35 contained in element 23 will normally intercept all globules of hydrocarbon fluid of appreciable size and cut up or shred them. The initial swirl or swirl of the gaseous fluid leaving the discharge end of the passage 27 will be maintained, to a large degree, in the passage of the mixture through the promiscuously disposed interstitial spaces between the loosely intertwined metallic filaments 35. Thus, the resultant stream emanating from vaporizing and mixing element 23 will be in the nature of a highly turbulent whirling fluid of a

haphazard or volleying character under high velocity.

Since in cold weather starting, carburetor outlet port 18, turbulator element 22 and vaporizing and mixing element 23 are necessarily cold, it will be readily apparent that some condensate will be formed along the lowermost end of conduit 14 and the abutting screen element 30 and metallic filaments 35. Perforations 29 have been 10 provided for permitting such condensate to drop back down into outlet port 18 of the carburetor 17 whereupon the condensate will be picked up by the oncoming stream of carbureted fluid.

It will be understood, that while I have illustrated members 22 and 23 as being separate units, they may be suitably secured together in any desired or preferable manner to form a single unit.

Referring, now, more particularly to Figure 4, I have illustrated a modified form of turbulating, vaporizing and mixing means. In this case, the element comprises a plate portion 40 shaped to suitably conform to the configuration of attaching flanges of an intake manifold and carburetor outlet port, and suitably provided with 25 perforations 41 to accommodate bolts such, for example, as 20. Centrally of the plate portion 40 a restricted passage 42 comprising a frusto-conical wall portion or nozzle 43 is provided. The under face of plate portion 40 is provided with 30 tangentially disposed grooves 44 in the manner and of the character illustrated in Figure 3. Two or more perforations 45 are provided to extend through the plate portion 40 at the juncture of the frusto-conical portion 43 with the base portion 35 for the purpose hereinbefore attributed to perforations 29.

At the discharge end of the restricted passage 42, a coarse mesh reticulated screen 46 having a depending annular flange 47 is provided, flange 47 being suitably secured to the inner periphery of frusto-conical portion 43 in any desired or preferred manner. A promiscuously intertwined loose mass of metallic filaments 48 is inserted into the restricted passage 42 and a second screen 49 having a depending annular flange 50 is inserted into the Venturi opening 42 and suitably secured to the inner periphery of the frusto-conical portion 43 in any suitable or preferred manner in spaced relation to the plate portion 40. 50 A suitable gasket 51 of cork or other composition may be interposed between the upper side of the plate portion 40 and the corresponding flange of the intake manifold to effectively seal the flanged joint except for the admission of 55 air from the outside atmosphere through the grooves 44.

The function and results attributable to the modification disclosed in Figures 1 to 3, inclusive, are likewise attributable to the modification disclosed in Figure 4, and it is therefore deemed unnecessary to further amplify the operation and function of the latter modification.

At the present time, there are in use in conjunction with internal combustion engines of the six cylinder type, intake manifolds which are provided with only one inlet port. In the cases of such manifolds, the outlet ports for the end combustion chambers or cylinders are located rather remotely from the inlet ports. Consequently, in cold weather starting conditions, hydrocarbon mixture being conducted through the body portions of such manifolds has a tendency to condense upon the inner walls thereof. To prevent the entry of condensed globules, under 75 such conditions, into the combustion chambers

or cylinders, I prefer to employ an additional vaporizer and mixer. Such a vaporizer and mixer is illustrated in Figure 5, being generally indicated at 60. Briefly, vaporizer and mixer 60 comprises a collapsible coarse mesh screen container 61 of generally cylindrical formation having one end 62 thereof of continuous semi-spherical formation. The other end comprises a planar portion of coarse mesh screen material 63 suitably secured to the cylindrical body portion of the container 61. Prior to the sealing of the container 61, it is filled with a loose mass of promiscuously intertwined metallic filaments indicated at 64 prior to the insertion of which a strip of expandable and collapsible metallic spring ring 65 is inserted into the body portion with the outer periphery thereof in contact with the continuous inner periphery of the container 61, ring 65 being disposed closer to the semi-spherical end than it is to the planar end and being suitably secured to the container in any desirable or preferred manner. The planar end 63 of the container is suitably secured to copper covered asbestos gasket 66 which is adapted to be seated in the usual gland seat provided therefor in the 100 block or head 15 at the point of connection of flanges 13 of the intake manifold 10 thereto.

The attributes, function and operation of vaporizer and mixer 60 are more comprehensively pointed out in the co-pending application 105 above noted and reference may be had thereto for a more comprehensive understanding thereof.

Referring now to the novel turbulating, vaporizing and mixing means of the present invention, due to the efficient nature of the means, 110 it will be readily apparent to those skilled in the art, that an oil feed dropping mechanism may be employed with the intake manifold to which the device is applied for lubricating valve stems and the upper portions of the combustion chambers or cylinders. It will be further noted that the metallic filaments provided in the vaporizing and mixing element 23 may be made from rust proof metal and where filaments of this character are employed, water may be introduced into 115 the intake manifold and thoroughly worked or vaporized by the air and hydrocarbon gaseous fluid stream, particularly in the case of internal combustion engines, so as to gain slow, long-drawn out explosions in the cylinders or combustion chambers. The advantages of the introduction of water vapor into an admixture of hydrocarbon gases fluid and air for combustion purposes in internal combustion engines are well known and will therefore not be here discussed. 120

It is to be further noted that the present invention as embodied in the forms illustrated in Figures 1 to 4, inclusive, is particularly applicable to low priced popular self-propelled vehicles where no moving parts are included in the intake manifold.

While I have illustrated the vaporizing and mixing element 23 as extending only partially into inlet port 14, the upper end thereof may extend the full length of such port thus substantially increasing the length of passage of the carbureted and turbulated hydrocarbon fluid and air through the mass of metallic filaments. The continuous upright wall of the screen container 30 may be slightly tapered upwardly its full 145 length so that it is maintained in spaced relation from the inner peripheral wall of port 14. Such tapering will permit of freer egress of the mixture with less surface retardation.

While I have disclosed various embodiments 150

of my invention, I do not wish to be limited thereto. As will be understood by those skilled in the art, certain changes may be made therein without departing from the essence of the invention or the spirit and scope of the appended claims.

What I claim and desire to secure by Letters Patent is:

1. Gaseous fluid turbulating, vaporizing and mixing means adapted to be interposed in a fluid conduit between a carburetor and an intake manifold, comprising a plate having a nozzle and a plurality of tangentially disposed grooves communicating with said nozzle for admitting air into the passage thereby agitating the carbureted fluid, and vaporizer and mixer means comprising a screen container having spaced walls of reticulated material, one of said walls having a reentrant portion of substantially the configuration of said nozzle and both of said walls having laterally extending marginal portions arranged in substantial contact, means serving as a gasket associated with the marginal portions of said screen walls, and means for clamping said vaporizer and mixer means against said plate with said nozzle disposed in said reentrant portion.
2. Gaseous fluid turbulating, vaporizing and mixing means adapted to be interposed in a fluid conduit between a carburetor and an intake manifold, comprising a plate having a bolting flange, a nozzle extending into the conduit in the direction of flow of the fluid and having a plurality of tangentially disposed grooves communicating with said passage for admitting air into the passage thereby agitating the carbureted fluid, and vaporizer and mixer means comprising a screen container having spaced walls of reticulated material connected together at their marginal portions to form a bolting flange and a promiscuously intertwined mass of loose material between said walls, one of said walls having a recess conformal with the outside of the nozzle to receive the same whereby the bolting flange of the mixer means may be secured against the bolting flange of said plate.
3. Gaseous fluid turbulating, vaporizing and mixing means adapted for use with carbureted gaseous fluids and the like comprising a supporting plate having a bolting flange and a nozzle and adapted to be interposed in a fluid conduit between a carburetor and an intake manifold, and vaporizing and mixing means comprising a wall of reticulated material conforming approximately to the outside of said nozzle, said wall

being supported upon the flange of said plate and adapted to be secured in place when the latter is secured in place in the conduit between the carburetor and the intake manifold.

4. Gaseous fluid turbulating, vaporizing and mixing means adapted to be interposed in a fluid conduit between a carburetor outlet and a manifold inlet, said means comprising an air inlet device including a plate having a nozzle extending from the central portion thereof and a peripheral marginal portion surrounding the nozzle, and a mixer element comprising a screen container having walls of reticulated material spaced apart centrally with their marginal portions in substantial contact, securing means arranged to secure the marginal portions of said walls together, one of said walls being made conformal with the outside of said nozzle to fit thereover and to permit the marginal portions of said walls to lie against the peripheral marginal portion of said plate when said air inlet device and said mixer element are disposed in place between the carburetor outlet and the manifold inlet.

5. Gaseous fluid turbulating, vaporizing and mixing means adapted to be interposed in a fluid conduit between a carburetor outlet and a manifold inlet, comprising an air inlet device including a plate having a nozzle extending from the central portion thereof and peripheral marginal portions surrounding the nozzle and provided with perforations therein, a mixer element comprising a screen container having walls of reticulated material spaced apart centrally with their marginal portions in contact, securing means embracing the marginal portions of said walls on both sides thereof to secure said portions together, said securing means having perforations therein adapted to register with the perforations in said plate, one of said walls being made conformal with the outside of said nozzle to fit thereover and to permit the securing means to lie against the peripheral marginal portion of said plate when said air inlet device and said mixer element are disposed in place between the carburetor outlet and the manifold inlet, said securing means being adapted to also lie against the manifold inlet and to serve as gasket means between said inlet and the marginal portion of said plate, and clamping means associated with said inlet and outlet and disposed in the perforations in said securing means and plate for maintaining said air inlet device and said mixer element in leak-tight relation between the carburetor outlet and the manifold inlet.
